(57) **CLAIM**

The ornamental design for a wireless headphone as shown and described.

DESCRIPTION

FIG. 1 is a front, right and top perspective view of a wireless headphone showing my design;

FIG. 2 is a rear, left and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a perspective view of a wireless headphone in an alternate position thereof; and,

FIG. 10 is a perspective view of a wireless headphone in an alternate position thereof.

1 Claim, 10 Drawing Sheets
